UNITED STATES PATENT OFFICE.

THOMAS A. WISEMAN, OF WINCHESTER, TENNESSEE, ASSIGNOR OF ONE-HALF TO
ROBERT T. WISEMAN, OF WINCHESTER, TENNESSEE.

LINE-WIRE FASTENER.

1,100,859.

Specification of Letters Patent. Patented June 23, 1914.

Application filed September 18, 1913. Serial No. 789,687.

To all whom it may concern:

Be it known that I, THOMAS A. WISEMAN, a citizen of the United States, residing at Winchester, in the county of Franklin and 5 State of Tennessee, have invented certain new and useful Improvements in Line-Wire Fasteners, of which the following is a specification, reference being had to the accompanying drawings.

10 This invention relates to new and useful improvements in line wire fasteners, and the primary object of the invention is to provide a device of this character provided with means for quickly and readily attaching telephone, telegraph, and similar wires 15 to a post.

A further object of the invention resides in providing a pair of clamping members with improved means for securing the same 20 to the post and designed for securely engaging the line wire.

A still further object resides in providing a device which is simple and durable in construction, inexpensive to manufacture, 25 and one which is very efficient and useful in operation.

With these and other objects in view, my invention consists in the novel features of construction, combination and arrangement 30 of parts as will be hereinafter referred to and more particularly set forth in the specification and claims.

In the accompanying drawing forming part of this application, Figure 1 is a plan 35 view of my device applied to use, showing the insulator cap in section. Fig. 2 is a side elevation thereof. Fig. 3 is a side elevation of one arm of the clamping member removed. Fig. 4 is a horizontal section as 40 seen on the line 4—4 of Fig. 2. Fig. 5 is an end elevation of one of the clamping members.

In describing the invention, I shall refer to the drawing in which similar reference 45 characters designate corresponding parts throughout the several views and in which—

1 indicates an insulator cap or the like applied to a post or other object, and to which a line wire 2 is adapted to be secured. In 50 order to secure said line wire to the insulator cap, I provide my improved device which consists first of a pair of arcuately designed wire clamps or the like 3 which are adapted to encircle said cap 1 in a groove 4 of the 55 latter, the ends of said wire members 3

being spaced from one another and arranged parallel when the same are so mounted on the cap. I also provide a pair of clamping members A and B, each of which comprises a pair of arms 5 and 6, the arms 5 being 60 provided with a plurality of openings 7 therein through which the parallel portions of the wire members 3 are disposed. Through this medium the clamping members A and B are secured to the cap 1 and 65 said clamping wires 3 tightly clamped about said cap.

The arm 5 of each of the clamping members A and B has a downwardly inclined projection 8 formed on the inner end 70 thereof, which projection is slotted, as shown at 9, and the upper edge of the projection is cut away or offset to form a notch 10. The arm 6, on the other hand, of each of the clamping members, is also provided 75 with a depending projection 11 which is designed to form a central tongue adapted for reception in the slotted portion 9 of the projection 8 on said arm 5. A pin or bolt 12 passing through the arms of the projection 8 of the one member and the projection 11 of the other member pivotally retains 80 said arms 5 and 6 together, and the inner edge of the projection 11 is cut away or offset to form a notch 13 which is complementary to the notch 10 in the other member. These notches 10 and 13 are adapted 85 to be brought together when the arms 5 and 6 are brought in clamping relation to one another and the opening so formed 90 between the notches is adapted to receive the line wire therethrough. In order to limit the swinging movement of the one arm with respect to the other, the projection 11 on the arm 6 is offset adjacent its lower end 95 to form a shoulder 14 which is adapted for engagement with the under face of the arm 5 when said arm 6 is swung to its open position. This shoulder obviously limits the movement of the arm 6 with respect to the 100 arm 5.

A loop or the like 15 is pivotally engaged adjacent the outer end of the arm 5 and is adapted to receive thereunder the outer end 105 of the arm 6 to retain said arms 5 and 6 in clamping relation to one another, and in order to permit the arm 6 to be readily received under said loop, the upper face of said arm 6 at its outer end, is beveled, as shown at 16. A spring member 17 is ar- 110

ranged in connection with said loop 15 to normally retain the latter in its effective or raised position so that when once disposed to its effective position, said loop is not 5 adapted to be readily removed through casual displacement.

It will be seen from the above description of the operation of the device that after the clamping members A and B have been 10 properly applied to the insulator head, a line wire may be quickly and readily clamped between the arms of said members A and B to be securely but removably held to said insulator cap. It will of course, be 15 understood that the line wire is held between the complementary notches 10 and 13 on the arms of the clamping members and the manner of applying the device to use will be readily understood from the above description 20 of the operation of the device.

It will be seen from the above that I have provided a device which is simple and durable in construction, inexpensive to manufacture and one which will be very efficient and 25 useful in operation and, while I have described the elements best adapted to perform the functions set forth, it is obvious that various changes in the form, proportion and in the minor details of construction may be 30 resorted to, within the scope of the appended claims, without departing from the spirit or sacrificing any of the principles of the invention.

Having thus described my invention, what 35 I claim, is:

1. A line wire fastener comprising a pair of clamping members, each composed of a pair of arms pivoted one to the other, said arms being provided with complementary 40 notches to receive a wire therethrough, means to limit the swinging movement of the arms with respect to one another and means to clamp said arms together, and wire members connecting said clamping members.

45 2. A line wire fastener comprising a pair of clamping members, each composed of a pair of arms pivoted one to the other, said arms being provided with complementary notches adjacent their pivotal points to receive a wire therethrough, means for limiting 50 the swinging movement of the arms and

the clamping members with respect to one another, spring held pivotal means for clamping said arms together, and wire members connecting said clamping members, said connecting means affording a means for securing the clamping members to an object. 55

3. In a line wire fastener, a clamping member consisting of a pair of arms, each of which is provided with a depending projection at one end thereof, the projection of one arm being slotted and the projection of the other arm being reduced in thickness and adapted to be received in the slotted portion of the other arm, means engaged 60 with the projections of said arms to pivotally secure the latter together, said projections being provided with complementary notches adapted to receive a line wire therethrough, means in connection with the projection on the last mentioned arm adapted 65 to engage portions of the first mentioned arm whereby to limit the pivotal movement of said arms with respect to one another, and means for clamping said arms together. 70

4. In a line wire fastener, a clamping member comprising a pair of arms, each of which is provided with a depending projection at one end thereof, the projection of one arm being slotted and the projection of the other arm being reduced in thickness to form a tongue adapted to be received in the slotted portion of the other arm, means engaged with the depending portions of said arms to pivotally connect the same together, 85 said projections being provided with complementary notches adapted to receive a line wire therethrough, the projection of the last mentioned arm being offset to provide a shoulder adapted for engagement with the 90 under face of the first mentioned arm to limit the movement of said arms with respect to one another, and a pivoted loop carried on the first mentioned arm adapted to engage the outer end of the second mentioned arm to clamp said arms together. 95

In testimony whereof I hereunto affix my signature in the presence of two witnesses.

THOMAS A. WISEMAN.
